LOOM FILLING FEELER

Kenneth E. Sanderson, Hopedale, Mass., assignor to Draper Corporation, Hopedale, Mass., a corporation of Maine

Application November 1, 1947, Serial No. 783,476

5 Claims. (Cl. 139—274)

1

This invention pertains to looms, and more particularly to loom filling feelers. More specifically, the invention is a novel filling feeler of the slip-action type.

Looms as commonly manufactured include a feeler which has as its function indicating incipient exhaustion of the filling mass on the bobbin in the loom shuttle, and initiation of a change in loom operation upon occurrence of such indication. The change may be initiated through action of electrical means or through action of mechanical means such as a linkage. Filling feelers are of many types, magnetic, electrical, mechanical, slip-action, and intermittent being a few of the broad classifications more or less well known. All loom filling feelers act to determine incipient filling exhaustion by feeling or contacting the filling mass remaining on the operating bobbin, and in most types of feelers motion of the lay is utilized to bring the filling mass into contact with the feeler for feeler action. In slip-action types of feelers, such as the side-slipping variety, incipient filling exhaustion is indicated by an abnormal movement of a filling feeler element, usually a slipping of the element along a bare portion of a bobbin, when the element no longer contacts with the filling mass on the bobbin. In certain types of weaving, as with fine or delicate filling, the repeated contacting of the filling by the feeler often results in either cutting of the filling or damage thereof to an objectionable extent. Intermittently acting feelers were devised to lessen the number of impacts of the filling against the feeler element, and thus save the filling; and other expedients were resorted to with the same view in mind, such as, for example, lightening the movable parts of the feeler to reduce impact loads borne by the filling on the bobbin. Most feelers are provided with one or more springs employed to cause return of the filling contacting element of the feeler to normal position after each feeling action, or to cause a filling exhaustion indicating movement, or both. Inevitably these springs, while in some types of feelers acting on very light feeler members, add to the pressure applied to the filling by the feeler. A somewhat improved type of slip action feeler was produced when a pair of magnets, one stationary and one on the feeler member, were substituted for the usual spring. But the magnet increased the weight of the feeler member to an objectionable extent. Prior feelers acting on the intermittent-operation principle are complicated, expensive, and subject to easy derangement of parts and are for those reasons not in wide usage.

2

With the above mentioned and other and obvious defects and disadvantages of prior filling feelers in mind, it is an object of the present invention to provide a simple, intermittently operating, side slipping filling feeler which does not suffer from the disadvantages afflicting prior art filling feelers. A further object is to provide an intermittently operating magnetically actuated filling feeler. An additional object is to provide a filling feeler for looms comprising a filling feeler member and a magnet acting to attract the member to normal feeling position and also acting to cause friction forces for retarding that movement. It is another object of the invention to provide a slip-action filling feeler having means providing a guideway, a single-piece filling feeler member guided by the means in a displacement movement from an active feeling position and in a return movement to the active feeling position, and magnet means acting to produce the return movement following occurrence of the displacement movement. It is another object of the invention to provide a feeler conforming to the description in the immediately preceding object, the magnet means also acting to create forces retarding the return movement of the filling feeler member to active feeling position. Another object of the invention is to provide an intermittently-acting filling feeler for looms, whose periods of activity automatically increase in frequency as incipient filling exhaustion approaches, whereby danger of missing an indication of incipient filling exhaustion is avoided.

The above and other objects that will become evident from a consideration of the whole of this disclosure are attained by the invention, a preferred embodiment of which is illustrated in the accompanying drawings, in which:

Fig. 1 is a plan view of a feeler according to the invention, with enough loom structure to illustrate application of the invention to an ordinary loom;

Fig. 2 is a view of a portion of the structure depicted in Fig. 1 with certain conditions changed, and on a larger scale;

Fig. 3 is a magnified view of structure depicted in Fig. 1, with certain conditions altered;

Fig. 4 is an enlarged isometric view of a feeler casing base and appurtenant means in partly disassembled relation; and

Fig. 5 is an isometric view of a permanent magnet employed in the preferred embodiment of the invention.

Only as much of conventional structure is depicted in the drawings as is necessary to a full

understanding of the invention. The preferred embodiment of the invention illustrated in the drawings is in the form of a filling feeler applied to a loom utilizing conventional mechanical linkage for initiating a change in loom operation upon occurrence of an indication of incipient filling exhaustion by the feeler; but it will be understood that the principles of the invention are equally applicable to looms utilizing other types of loom-operation change-initiating means, as, for instance, electrically operated means. The invention comprehends a filling feeler which acts to "feel" or come into contact with the filling mass on the active bobbin only occasionally while the filling mass is still of relatively large diameter, but which increases the frequency of the feeling actions as the filling mass contacted by the filling contacting element of the feeler decreases in diameter, until, at the point when incipient weft exhaustion is imminent, the feeling actions occur every time the bobbin is brought toward the feeler. This is in contradistinction to the action of other intermittently acting feelers, wherein the frequency of the feeling actions is fixed and invariable throughout the entire period of removal of filling from a bobbin, and allows successful operation of an intermittently acting filling feeler without the necessity of setting the feeler so loom-operation change will be effected with a relatively large amount of filling remaining on the bobbin. The latter setting of previously known intermittently acting feelers was necessitated by the fact that the bobbin might otherwise become exhausted while the feeler was inactive.

Referring to the drawings, there is designated generally by the numeral 10 certain conventional loom structure at the left hand end of the loom lay and including a binder 11 and front box plate 12 forming with a part 13 of the lay end a shuttle box 14 into which a shuttle 15 is received and from which the shuttle is picked by a picker 16 in uniform or variable cyclically repeated operations. Firmly supported in the shuttle is a bobbin 17 carrying a winding or mass of filling 18. The shuttle will in normal operation of the loom be received in box 14 at the termination of each alternate pick and will be moved forwardly (downwardly as viewed in Figs. 1, 2 and 3) as the filling pick is beaten into the cloth, and subsequently moved rearwardly (toward the top of the figure in Fig. 1) as the lay recedes from the fell of the cloth. The above enumerated loom structure and the indicated operation thereof are well known by all persons skilled in the art and need not be herein further described. Per se they form no part of the present invention.

According to the invention there is firmly supported at its inner end, as on a convenient part of the loom frame (not shown), a feeler support 20 in the form of an arm having a relatively flat upper face 21 at its other end; the support being of any suitable shape and such as to partake of vibration of the loom part incident to loom operation. Mounted upon face 21 of the support as by means of a screw 22 passing through the support from the bottom thereof is a feeler base 23 of non-magnetizable material such as brass, aluminum, or synthetic resin and having a tapped hole 24 to receive screw 22 (see Fig. 4). Base 23 is of generally rectangular plan-form and is provided with opposed side wall portions 25, 26 and a floor portion 27 between the side walls, these portions forming, in conjunction with a preferably transparent feeler cover 28 an open-

ended guideway. Cover 28, which may be formed of a transparent synthetic resin, may conveniently be secured to base 23 by means of a screw 29 passing through a hole formed in the cover and threaded into a suitable tapped hole 30 formed in base 23. Acting in conjunction with the above described guideway as subsidiary guide means is an abutment 31 within the guideway and preferably but not necessarily formed as an integral portion of base 23. The guideway and abutment have functions that will hereinafter be more fully disclosed.

Movably supported in the above mentioned guideway and guided therein by the structures forming the guideway is a single element filling feeler member 32 which has an active feeling position to be more specifically defined hereinafter and which during normal loom operation partakes of normal rectilinear reciprocatory movements comprising displacement movements from, and return movements to, the active feeling position. In the illustrated embodiment of the invention feeler member 32 is made of ferro-magnetic material and is equipped with a tip 33 of fibrous material such as "Micarta"; but it will be understood that in equivalent constructions member 32 may be made of another material, and the tip may alternatively be employed or omitted from the member in either case. By the term "single-element filling feeler member" as herein employed, I mean a filling feeler member having but a single part within the guideway.

In the illustrated embodiment of the invention, a depression or cavity 34 is formed below the floor 35 in base 23, preferably at a corner of the floor as depicted in Fig. 4, and of a shape therein shown in detail. Arranged in the cavity and adjustably movable therein transversely of the aforementioned guideway is a magnet means, preferably but not necessarily in the form of a shaped permanent magnet 35. I have found that a magnet of "Alnico No. 4," suitably charged by a magnetizing force of approximately 6000 ampere turns per linear inch, and aged either by natural aging for at least twelve hours or artificially by means of a demagnetizing field accomplishing an approximately 7% reduction from peak magnetization, is suitable for the purposes of the invention; however, other suitable permanent magnet and/or electromagnet means may be employed. Magnet 35 is formed of a shape indicated in detail in Fig. 5 and is of such size as to fit snugly in cavity 34 with capability for the mentioned transverse motion; and has shaped indentations 36, 37 at one side thereof and an indentation 38 at the opposite side. Indentation 37 is of such shape and size as to form opposed projections 39, 40 which straddle abutment 31, and indentation 36 is of such shape and size as to receive therein an end of a small compression spring 41 (see Fig. 3) whose opposite end presses against abutment 31 and which tends to move the magnet away from the abutment. Positioning magnet 35 against the action of spring 41 is a screw 42 bearing against the magnet in indentation 38 and threadably mounted in a tapped hole 43 formed in the side wall 25 of base 23. Suitable means such as a lock nut 44 may be employed to maintain screw 42 in adjusted position. The magnet preferably is so charged that its polar axis is approximately parallel with the guideway, that is, as indicated by the polar marks indicated on the magnet. It will be understood however, that the magnet may be arranged with its magnetic axis transverse to the guideway. This becomes desir-

able when the loom is to be operated at exceptionally high speeds. In either positioning of the magnet it is immaterial which is the "north" or the "south" pole.

Abutment 31 is formed to have a friction producing face 31a generally parallel with the axis of the guideway and acting to exert frictional forces on feeler member 32 when the latter is moved longitudinally along the face and drawn thereagainst by attraction exerted by magnet 35.

Feeler member 32 is preferably formed by deforming a simple rod to provide a tip end 32a laterally offset from the main longitudinal stretch or body portion 32b of the member and substantially parallel therewith, the offset being accomplished by a length 32c extending substantially at a right angle to the body portion 32b. A foot 32d is formed on the feeler member by bending and reversely bending the rod as indicated in Fig. 3. Body portion 32b and foot 32d are so relatively formed and proportioned that as the reverse bend in the foot slides along wall 25, portion 32b may slide in contact with the friction face 31a of abutment 31. According to the invention the feeler member is adapted to assume an active feeling position as indicated in Fig. 1, which is the rearwardmost position the member may normally assume, and in which position the foot of the member is substantially in contact with an end face of magnet 35 and tip 33 is positioned to be contacted by the filling 18 or bobbin 17 as the lay and shuttle move forwardly. From this active feeling position the member may be given a displacement movement by action of the forwardly moving filling 18 and the member may subsequently be returned to this position by attractive action of magnet 35, either unaided or aided by vibration of base 23 due to vibration inherent in loom operation. Fig. 1 illustrates the relationship of the feeler parts and the filling just at the moment the filling contacts tip 33. Fig. 3 depicts an example of the relationship of the feeler parts when the member has been given a displacement movement by the filling and is undergoing return movement to active feeling position under the influence of magnet 35, the filling having moved away from tip 33. It will be noted that foot 32d is attracted by the magnet and body portion 32b is drawn or attracted by the magnet into frictional engagement with abutment 31, the latter action creating friction forces which retard the return movement of the feeler member to active feeling position. These friction forces are aided by the retarding effect of eddy currents induced in the feeler member as the latter moves in the magnetic field of the magnet. It is evident that when the filling mass on the bobbin is of maximum diameter the aforementioned displacement movement will be a maximum and consequently the time required for the return movement to active feeling position will be a maximum, the retarding force remaining substantially constant throughout the return movement; and further that as the filling mass decreases in diameter as the filling is used, the displacement movements will decrease and consequently the time required for the return movement will decrease. The parts may be so adjusted that with the filling mass at its maximum diameter the displacement will be such that return movement of the member will require a period covering as many as eight, or even more, cycles of shuttle operation (i. e., as many as sixteen or more picks) for its completion; and so that with the filling mass diameter reduced to a point where incipient exhaustion of the filling is im-

minent or near at hand, the displacement will be such that return movement of the member will require a period of less than one cycle of shuttle operation (e. g., one pick) for its completion.

Thus it is evident that the feeler is intermittently acting in its operation, and automatically increases the frequency of the feeling actions as the yarn mass diameter decreases, commencing with a high number of cycles of shuttle operation per feeling action when the bobbin is full and changing gradually to a detecting action for each cycle of shuttle operation shortly preceding and during occurrence of incipient filling exhaustion.

As filling exhaustion becomes imminent or near, the filling mass remaining on the bobbin is reduced until a stage of operation is reached whereat no filling remains between the bobbin and the tip of the feeler as the bobbin approaches the feeler. At this stage, only a small amount of filling remains on the bobbin and that is spaced from the line of contact with the feeler tip, and final exhaustion of the filling is incipient. At this stage a change in loom operation, such as replacement of the nearly exhausted bobbin by a full bobbin, is desirable; and in the illustrated embodiment of the invention need for such change is indicated by an abnormal lateral slipping movement of the feeler tip along the bared bobbin as indicated in Fig. 2. This slipping action occurs in the illustrated structure by virtue of the offset relationship of the tip with respect to foot 32d and body portion 32b of the feeler member and to the fact that the normal friction effect of the filling mass on the tip no longer obtains. The bobbin may and desirably does have a very smooth surface in that portion of its surface area which could enter into contact with the feeler tip, to aid in allowing the mentioned slipping of the tip along the bobbin. The indication of incipient filling exhaustion thus given by the feeler member may be variously utilized to initiate a change in loom operation. In the illustrated embodiment of the invention the indication of incipient exhaustion, represented by the abnormal lateral movement of the feeler member, is utilized to move a rod 45 extending into the guideway through a hole 46 in side wall 26 of the feeler casing. Movement of this rod may be employed in any manner well known in the art to bring about the desired change in loom operation. Rod 45 and the devices brought into action thereby may be of well known construction and are not a part of the present invention, and since several forms of such devices are well known in the art none are herein further disclosed.

It will be understood that it is desirable to reduce the impact load applied to the filling when the latter contacts the feeler tip, and accordingly the feeler member is made as light as is consistent with the requirements of durability, certainty of proper performance and other obvious essentials of an operative structure. As an aid in making certain the full side-slipping movement of the feeler tip once that movement is commenced, a depression 47 is provided in side wall 25, into which depression the reverse bend of foot 32d is adapted to move as soon as side-slipping movement of the feeler tip is under way. During side-slipping movement of the tip the feeler member rotates about a shifting axis located at first near the lower right-hand corner of magnet 25 (as viewed in Fig. 2). The result of initial stages of this rotation is movement of the reverse bend of foot 32d into depression 47, whereupon the reverse bend is held against the curved face of the

depression partly through attraction of magnet 35 but principally due to inertia forces. Thus any increased resistance to continuation of the side slipping action, as for example, that offered when rod 45 is met with by portion 32b of the feeler member, is effectively overcome.

It will be understood that the feeler member may be bounced forwardly away from the filling normal loom operation, especially when the filling mass is of large diameter. The action in this respect is much like that of a ball when struck by a bat. To prevent excessive displacement movement of the feeler member if and when this condition occurs, the feeler is provided with a limiter preferably in the form of a spring blade 48 having a lateral offset 48a whose plane is formed at a right angle to that of the body portion 48b of the blade. The offset is provided with an aperture whereby it is secured in a close fitting recess formed in side wall 26 as by means of a screw 49 threaded into a complementary tapped hole formed in the side wall, all as indicated in Figs. 3 and 4. Body portion 48b has a short length, approximately equal to the length of offset 48a, arranged to lie closely in contact with side wall 26, from which it sharply diverges at 48c, by a sharp bend, for a small distance toward the center of the guideway. Thence body portion 48b extends generally parallel to side wall 26 for most of its length but is provided with a small bend or stop at 48d, shaped as shown in the figures. This bend or stop is placed at a location in body portion 48b sufficiently far forward from offset 48a to accommodate rearwardly thereof the maximum normal operating displacement movement of the feeler member, the stop acting to stop foot 32d of the member in those instances wherein the feeler member partakes of such maximum normal operating displacement. The stop accordingly acts to prevent excessive displacement movements of the feeler member, and may conveniently also act as a holder to hold the feeler member out of operation, as is sometimes desirable in loom operation. This holding action is effected when the feeler member is manually forced forwardly by hand to the limit of its possible forward travel as determined by offset 32c contacting the rear end of side wall 26. When so forced, the end of foot 32d compresses the bend of spring 48 at 48d and the reverse bend of the foot is tightly held against side wall 25, thus holding the feeler member out of operation.

By virtue of the adjustability of magnet 35 the feeler may readily and successfully be accommodated to looms operating over a wide range of speeds, without further modification. Since a loom operating at a relatively high rate of speed subjects its component parts and attachments to more severe vibration and vibration of a relatively high frequency, the tendency of the feeler member is to make a faster return movement to active feeling position subsequent to displacement therefrom. This tendency is effectively overcome by adjusting magnet 35 so it nearly contacts body portion 32b of the feeler member, whereby the friction forces between that member and abutment 31 are intensified. In extremely fast-operating looms it may even be found to be desirable to adjust the magnet so it actually contacts the feeler member and takes part with or replaces abutment 31 as a guide member. In the case of low loom operating speeds, however, vibration is much less severe and of lower frequency, hence magnet 35 is adjusted to remain spaced away from body portion 32b of the feeler

member, thereby creating reduced friction forces and likewise a reduced retardation of the return movement of the feeler member to active feeling position. Spring 41 acts to maintain the magnet bearing against screw 42 in any of the positions of the screw. While it is convenient to rely upon vibration incident to loom operation to intermittently vary the friction forces between abutment 31 and the feeler member, magnet 35 may be of such strength and disposition and so adjusted as to impart the hereinabove described return movements of the member to active feeling position without the aid of such vibration.

Having fully disclosed a preferred embodiment of my invention it is evident that changes and modifications will occur to those skilled in the art after consideration of my disclosure. Accordingly I do not desire to be limited to the specific details of the disclosed embodiment but

20 what I claim is:

1. A slip-action filling feeler for looms, comprising, in combination: a feeler casing including means forming a guideway and an abutment in the guideway; a filling feeler member having 25 an active feeling position and guided in said guideway by said means for normal sliding displacement movement from said position and normal sliding return movement to said position and, for filling exhaustion indicating movement 30 abnormal with respect to said normal sliding displacement and return movements, said member sliding by one side of said abutment in partaking of said normal movements; and a magnet having opposite poles which are spaced, one at one 35 side and the other at the other side of said abutment, the opposite side of said abutment acting through certain components of the magnetic forces incident to its entire magnetic field to attract the member against the abutment to create 40 frictional forces therebetween and further acting through other components of the magnetic forces which comprise its entire magnetic field, and upon another portion of the feeler member to attract and draw said member to said active feeling 45 position subsequent to occurrence of any of said movements.

2. In combination in a loom: a filling feeler support subject to vibration inherent to loom operation; a shuttle box oscillating toward and 50 away from said support and having a shuttle therein during certain of said oscillations; a filling carrying bobbin in said shuttle; a filling feeler casing fixed on said support and comprising means forming a guideway and an abutment 55 within said guideway; a filling feeler member having a tip and having an active feeling position wherein said tip is in the path of the bobbin in said shuttle, said member being at least partly within and guided in said guideway by said 60 means during a displacement movement from said feeling position induced by contact between the member and the filling on said bobbin and also so guided during subsequent return movement to said feeling position; and a magnet and 65 means adjustably fixing the magnet in said casing, said magnet acting to return said member to said feeling position subsequent to displacement thereof from said position by action of said filling and bobbin and further acting during said 70 return to draw said member against said abutment and thereby create friction forces retarding said return movement, said friction forces being intermittently varied by said vibration.

3. A side slipping filling feeler for looms, comprising the combination of a magnetic feeler

member including an elongated, straight portion and an angularly formed guiding portion, supporting and guiding means for said feeler member within which the said member is constrained to move to and from an active filling engaging position and to be rotated bodily upon substantial exhaustion of filling thereby to initiate replenishment, an abutment on said support positioned to guide and to friction said feeler in its movements to and from active, filling engaging position, and a magnet positioned wholly at the opposite side of said abutment from said feeler and positioned in a plane therewith, acting in one direction upon said feeler to draw the elongated, straight portion thereof against the abutment, and substantially at right angles to said one direction and upon the angularly formed guiding portion, to move it toward its active, filling engaging position.

4. A side slipping filling feeler for looms, comprising the combination of a feeler member, supporting and guiding means for said feeler member within which the said member is constrained to move to and from an active filling engaging position and to be rotated bodily upon substantial exhaustion of filling thereby to initiate replenishment, said feeler comprising an elongated, substantially straight portion of magnetic material, a filling contacting member at one end thereof, and an angularly formed magnetic guiding portion at its opposite end, an abutment extending from said support and positioned so as to guide the said straight portion of the feeler in its movements to and from active, filling engaging position, and a magnet positioned at the opposite side of said abutment from said feeler and in a plane therewith so as to draw the feeler by its attraction upon the substantially straight portion thereof, into engagement with the abutment, and simultaneously by its attraction upon the angularly formed portion of the feeler, to move it toward its active, filling engaging position.

5. A side slipping filling feeler for looms, comprising the combination of a feeler member, supporting and guiding means for said feeler member within which the said member is constrained to move to and from an active filling engaging position and to be rotated bodily upon substantial exhaustion of filling thereby to initiate replenishment, said feeler comprising an elongated magnetic portion, a filling contacting tip and an angularly disposed magnetic guiding portion at the end of said elongated portion opposite said tip, an abutment extending from said support and positioned so as to guide the said elongated portion of the feeler in its movements to and from active, filling engaging position, and a magnet positioned at the opposite side of the abutment from said elongated portion of the feeler having opposite poles, one at one side and the other at the other side of said abutment for drawing the feeler by its attraction upon the magnetic elongated portion thereof into frictional contact with the abutment, said magnet further being of such strength and so relatively positioned with respect to the angularly disposed portion of the feeler and to the relatively straight portion at the abutment, that is, in coaction with natural vibrational forces within the loom structure, returns the feeler to filling engaging position after a number of cycles of operation which varies with the extent of movement of the feeler from its normal, filling engaging position.
